Primary Examiner — Eric Goodman*Assistant Examiner* — Megan M Majcher Hartnett(74) *Attorney, Agent, or Firm* — Saidman DesignLaw Group, LLC(57) **CLAIM**

The ornamental design for a display screen with graphical user interface, as shown and described.

DESCRIPTION

FIG. 1 is a front view of a first embodiment of a display screen with graphical user interface showing our new design. The outermost broken line is a showing of the display screen and forms no part of the claimed design. The features shown in broken lines in the drawings depict environmental subject matter only and form no part of the claimed design.

1 Claim, 1 Drawing Sheet(56)
